(57) **CLAIM**

The ornamental design for a bottle, as shown and described.

DESCRIPTION

FIG. 1 is a front perspective view of the bottle in a filled state showing my new design;

FIG. 2 is a front view thereof;

FIG. 3 is a rear view thereof;

FIG. 4 is a left side view thereof;

FIG. 5 is a left side view thereof;

FIG. 6 is a top view thereof;

FIG. 7 is a bottom view thereof;

FIG. 8 is a front view of the bottle in unfilled state;

FIG. 9 is a top view of the bottle of FIG. 8 in unfilled state;

FIG. 10 is a right side view of the bottle of FIG. 8 in an unfilled state; and,

FIG. 11 is a left side view of the bottle of FIG. 8 in an unfilled state.

Any broken lines which may be shown in the views are for illustrative purposes only, and form no part of the claimed invention.
